UNITED STATES PATENT OFFICE.

CHARLES H. MILLER, JR., OF BUFFALO, NEW YORK, ASSIGNOR TO THE
BUFFALO CURTAIN FIXTURE COMPANY, OF SAME PLACE.

CURTAIN-FIXTURE.

SPECIFICATION forming part of Letters Patent No. 293,188, dated February 5, 1884.

Application filed March 6, 1877. Renewed March 31, 1879.

To all whom it may concern:

Be it known that I, CHARLES H. MILLER, Jr., of the city of Buffalo, in the county of Erie and State of New York, have invented certain new and useful Improvements in Curtain-Fixtures, which improvements are fully set forth in the following specification, reference being had to the accompanying drawings.

My invention relates to that class of curtain-fixtures which are employed with curtain-rollers provided with a spring for winding up the curtain, and which are generally so constructed that the movement of the curtain-roller will be unrestricted when the curtain is permitted to be wound up with considerable speed, while the movement of the curtain-roller is stopped automatically when the curtain is raised slowly.

My invention relates more particularly to the construction of the device for locking the curtain-roller, and its nature will be fully understood from the following description.

In the accompanying drawings, Figure 1 is a longitudinal section of a curtain-roller provided with my improvements. Fig. 2 is an end view of the catch-plate, with one of the catches engaged. Fig. 3 is a similar view with both of the catches disengaged. Fig. 4 is a rear view of the end plate. Fig. 5 is a horizontal section thereof.

Like letters of reference refer to like parts in each of the figures.

A represents the curtain-roller provided with a longitudinal bore or cavity, in which is arranged the spring b.

C is a bar or rod, arranged axially within the bore of the curtain-roller, to which latter it is secured at the inner end.

D is a plate, arranged within the bore of the curtain-roller, near its outer end, and provided on its outer side with a shank, d, having its protruding end flattened on one side, as shown in Figs. 2, 3, and 5, and engaging in a correspondingly-shaped opening in the bracket E. The plate D is provided on its inner side with a socket, in which the end of the bar C turns when the roller A is rotated.

F represents the catch-plate, arranged at the open end of the curtain-roller, and provided with a central opening, through which passes

the shank d. The plate F is provided on its outer side or face with two parallel guide bars or ribs, f f, arranged on opposite sides of the shank d.

g g represent two catches, arranged between the guide-bars f f on opposite sides of the flattened shank d, so as to be capable of sliding toward and from the shank. The inner ends of the catches g are formed with curved or concave faces, adapted to rest upon the round face of the shank d, and with lips or shoulders 60 on opposite sides of a central line, to engage between the flattened side of the shank and each of the ribs f, as clearly shown at Fig. 2.

The catch-plate F is provided on its rear side with several small projections or pins, i, 65 entering corresponding cavities in the annular end of the curtain-roller, so as to cause the plate F to revolve with the latter. The plate F is secured in place on the curtain-roller, and the catches g g confined by a ferrule or sleeve, 70 G, placed over the plate and the end of the curtain-roller, as clearly shown in Fig. 1. The opposite end of the curtain-roller is provided with a plate and journal, H, in the ordinary manner.

The spring b is secured at one end to the plate D, the coils surrounding the central rod or core, C, and the other end of the spring passes out through a slot or opening in the roller, and is secured in place, as clearly shown 80 in Fig. 1. The spring b being wound up and the roller supported in the brackets, the curtain, when released, is raised by the force of the spring. When the curtain-roller revolves rapidly in raising or lowering the curtain, the 85 stops g g are thrown against the surrounding sleeve G by the centrifugal force, and thereby kept out of engagement with the flattened shank d. Upon allowing the curtain to rise slowly, one of the stops g will by gravity drop 90 down and engage with its projecting lip against the flat side of the shank d, as shown in Fig. 2, thereby preventing the further rotation of the curtain-roller and securely locking the same in position. Upon drawing the curtain 95 downward the stop engaged with the flattened shank is forced out of engagement therewith by the concave portion of the stop riding upon

the round portion of the shank, when the curtain is free to be raised or lowered, as may be desired.

The parts of my improved device for locking the curtain-roller in position are each 5 readily cast of suitable metal, and the whole secured together without any screws or rivets.

I do not claim a curtain-roller having the bar C secured to or made in one piece with the 10 roller A; but

What I claim as my invention, and desire to secure by Letters Patent, is—

1. The combination, with a spring curtain-roller having flattened shank *d*, of one or more

sliding catches, *g*, provided on the inner side 15 with a concave portion and projecting lip, as and for the purpose shown and described.

2. The combination, with a spring curtain-roller having a flattened shank, *d*, of the plate F, provided with parallel guide-bars *f f*, and 20 one or more sliding catches, *g*, provided on their inner side with a concave portion and projecting lip, substantially as and for the purpose hereinbefore set forth.

CHARLES H. MILLER, JR.
